UNITED STATES PATENT OFFICE.

WIRT S. SCOTT, OF EDGEWOOD PARK, PENNSYLVANIA, ASSIGNOR TO WESTINGHOUSE ELECTRIC & MANUFACTURING COMPANY, A CORPORATION OF PENNSYLVANIA.

CONTROL SYSTEM FOR VENTILATING APPARATUS.

1,358,790.

Specification of Letters Patent. Patented Nov. 16, 1920.

Application filed May 23, 1919. Serial No. 299,303.

To all whom it may concern:

Be it known that I, WIRT S. SCOTT, a citizen of the United States, and a resident of Edgewood Park, in the county of Allegheny 5 and State of Pennsylvania, have invented a new and useful Improvement in Control Systems for Ventilating Apparatus, of which the following is a specification.

My invention relates to electrically heated 10 ovens and particularly to systems of control for electrically heated enameling ovens.

The object of my invention is to control the supply of energy to the electrically operated heating coils of an oven of the above 15 designated character by means of an electrically operated means for ventilating the oven.

An electrically heated enameling oven, of the intermittent type, as usually constructed, 20 comprises a suitable oven chamber provided with electric heating coils and with suitable doors for inserting and removing the work. Freshly japanned metal objects may be placed in the oven, the doors closed, and 25 the heating coils then be energized to raise the temperature of the air and of the metal objects in the oven sufficiently to bake the enamel. As the temperature of the metal objects is increased, oil and tar vapors are 30 driven out of the enamel. As the vapors escape to the outside atmosphere through small ventilating pipes, some portions of them will condense on the inner surfaces of these pipes and harden. After long continued use of the oven, a considerable 35 amount of material may thus be deposited in the vent pipes, and, if continued long enough, these pipes may become clogged. The deposited material may also be coked, 40 because of the continued heating, and its ignition temperature may be lowered by reason of such coking.

If a quantity of freshly enameled metal objects is placed in such an oven while heated because of previous operation, the naphtha volatiles in the enamel may be driven out very rapidly as soon as the heating coils are again energized. An explosive mixture may thus be formed in the oven, and spontaneous combustion may take place in the 45 vent pipes because of the coked deposits therein. The flame thus produced may be communicated to the exterior of the oven and cause an explosion of the mixture of air and volatile vapors.

In practising my invention, I provide an exhaust fan, driven by an electric motor, for ventilating the oven chamber, and place a minimum-current relay in the motor circuit. The circuit of the electrically operated heating coils is controlled by an electro-magnetic switch, and a circuit is so arranged that the operation of the underload relay will cause the electro-magnetic switch to open and deenergize the heating coils. As 60 long as the vent pipe is not clogged and the motor load is normal, the relay will be in its normal position. If the vent pipe becomes so clogged as to reduce the quantity of air that can be removed by the exhaust 65 fan, to an amount that may cause an explosive mixture, the motor current will also be reduced. The minimum-current relay in the motor circuit will then operate to short circuit the holding coil of the electro-magnetic switch in the heater circuit, causing 70 it to open and thus deenergize the heater coils.

A thermostat is provided for protection of the oven against overheating and operates 80 to open the heater circuit in case of a dangerously high temperature. An on-and-off push-button station is so arranged that the current through the heater coils may be interrupted, if desired, independently of either 85 of the above mentioned agencies.

The single figure of the drawing is a diagrammatic outline of the connections of the device embodying my invention, as applied to an electrically heated enameling 90 oven.

In the drawing, an inclosed oven chamber 1, having suitably arranged doors (not shown) for inserting and removing the work, is provided with a vent 2. A pipe 3 connects the vent 2 to an exhaust fan 4 that is driven by an electric motor 5. In the drawing, the exhaust fan is shown as being direct-connected to the driving motor, but any suitable connecting means may be employed. A fused switch 6 connects the motor 5 to a supply circuit 7, and a suitable controller (not shown) may be employed to start the motor. In one of the motor leads is placed a minimum-current relay 8, the operation of which will be described later in detail.

A supply circuit 9 furnishes energy to heater coils 10 in the oven chamber, through an electromagnetic switch 11. A control cir- 110

cuit is connected to the supply circuit 9 through a fused switch 12, an on-and-off push-button 13 and conductors 14, 15 and 15a, and comprises a double-contact thermostat 16a located in the oven chamber and a circuit-closing relay 17. The relay 17 has a main bridging contact member 18 and an auxiliary bridging contact member 19. The main contact bridging member 18 closes a circuit derived from supply circuit 7 and comprising conductors 20, and 20a, the coil of the electromagnetic switch 11 and a return conductor 21. The auxiliary contact bridging member 19 closes a circuit comprising a conductor 22 connected to the fixed end of the bimetallic strip 16 of the thermostat 16a, a fixed resistance 23, and a conductor 24 that is connected to the "low" contact terminal 25 of the thermostat and also connected to conductor 14. The "high" contact terminal 26 is connected to the conductors 15 and 15a. The contact terminals of the underload relay 8 are connected, respectively, to the conductor 15a by means of a conductor 27, and to the conductor 22 by means of a conductor 28.

Assume that the circuits 9 and 7 are energized and that the switches 6 and 12 are open and the bimetallic strip 16 to be in contact with the "low" contact terminal 25, the operation of the device and the system is as follows: Close the switch 6 and bring the motor 5 up to normal speed by means of the controller. With a full opening of the vent pipe 3, the exhaust fan 4 will remove the normal amount of air, and the load on the motor 5 will be normal. The current in the coil of the relay 8 will, therefore, be normal and will operate to hold the armature in such position that the contact bridging member will not make operative connection between the contact terminals of the conductors 27 and 28. The switch 12 may now be closed and the push button 13 operated to close the control circuit. This circuit will be as follows; from one side of the supply circuit 9, through one member of the switch 12, through the push button 13, conductor 14 to contact terminal 25, through the bimetallic strip 16 to the conductor 22, through the coil of the relay 17 to the conductor 15a, the conductor 15, the second member of the switch 12 and to the other conductor of the supply circuit 9. This will operate to close a circuit through the coil of the electro-magnetic switch 11 as follows; from one conductor of the circuit 7, to the conductor 20, through the bridging contact member 18 to the conductor 20a, through the coil of the switch 11 and conductor 21 to the other conductor of the supply circuit 7. The switch 11 will close and connect the circuit 9 to the heater coils 10 in the oven chamber.

65 The bridging contact member 19 of the

relay 17 closes an auxiliary circuit from the conductor 22 to the fixed resistance 23, through the conductor 24, to the "low" contact 25 of the thermostat and also to conductor 14. If the temperature in the oven 70 chamber rises so that the bimetallic strip 16 becomes disengaged from the contact terminal 25 but does not engage contact terminal 26, the following circuit will operate to keep the relay 17 in its closed position; 75 from one conductor of the supply circuit 9 through one member of the switch 12, conductors 15 and 15a, the coil of the relay 17, the bridging contact member 19 to the resistance 23, conductors 24 and 14, push button 13, the other member of the switch 12 and to the other conductor of the circuit 9.

In case the vent 2 or the vent pipe 3 become clogged to such an extent as to allow the removal of relatively small amounts of 85 air and volatile gases from the oven chamber 1,—a condition that might give rise to explosive mixtures in the oven—the current in the motor will be correspondingly decreased. This will allow the armature of 90 the relay 8 to drop and establish a short circuit across the terminals of the relay 17 as follows; through conductors 27 and 15a, the coil of relay 17, and conductors 22 and 28 to the other contact terminal of the relay 8. The armature of the relay 17 will drop and open the circuit through the coil of the magnetic switch 11. This switch will then open and interrupt the supply of energy to the resistors 10, and the liberation 100 of further quantities of volatile vapor from the enamel will, to a great extent, be prevented. Thus, conditions in the exhaust system that might cause explosive mixtures in the oven chamber will operate to deenergize 105 the heating coils and thus render the operation of such ovens safer than heretofore.

If the temperature in the oven chamber 1 were to increase to such high value as might result in damaged work, the bimetallic strip 16 of the thermostat 16a will engage the contact terminal 26 and will short circuit the coil of the relay 17, the circuit being as follows; from one side of the supply circuit 9, through one member of switch 12, conductor 15 to contact terminal 26, through bimetallic strip 16, conductor 22, contact bridging member 19, through resistance 23, conductors 24 and 14, push button 13, the other member of switch 12 to the return conductor of circuit 9. This will cause the switch 11 to open, as described above in connection with the operation of the relay 8, and will operate to deenergize the heating coils.

The circuit of the relay 17 may also be opened at any time by means of the push button 13, this action resulting in opening the switch 11 and deenergizing the heating coils 10. It is to be understood, however,

130

that the push button 13 and the thermostat 16a are not essential elements of my invention but are parts of a complete control system in combination with the device embodying my invention.

Various modifications of the device may be made without departing from the spirit and scope of my invention, and I desire that only such limitations shall be imposed as 10 are indicated by the prior art or are specifically set forth in the appended claims.

I claim as my invention:

1. The combination with an oven structure comprising a chamber having an outlet for 15 the removal of foreign substances, electric heating means for said oven, and means for controlling said electric heating means, of means for positively removing foreign matter from said oven, and means whereby the 20 decrease of the flow caused by said removing means causes the operation of said controlling means to interrupt the operation of said heating means.

2. In an electric oven, the combination 25 with an oven chamber having an outlet for the removal of foreign substances, means for electrically heating said oven, and means for controlling said electrical heating means, of means for removing foreign substances 30 through said outlet, and means whereby the cessation of operation of the withdrawing means causes the controlling means to interrupt the operation of said heating means.

3. In an electric oven, the combination 35 with an oven chamber having an air outlet, means for electrically heating said oven, and means for controlling said electrical heating means, of means for drawing air and volatile vapor from said chamber through said 40 outlet, and means for causing said control-

ling means to interrupt the operation of said heating means under predetermined conditions dependent upon the amount of air and volatile vapor drawn through said outlet.

4. In an electric oven, the combination 45 with an oven chamber having an outlet for foreign matter, means for electrically heating said oven, and means for controlling said electrical heating means, of an exhaust fan connected to said outlet, an electric motor 50 for operating said fan, an underload relay in said motor circuit, said relay causing the operation of said controlling means to interrupt the operation of said heating means under predetermined conditions dependent 55 upon the amount of foreign matter withdrawn by said fan.

5. In an electric oven, the combination with an oven chamber having an air outlet, means for electrically heating said oven, and 60 means for controlling said electrical heating means, of means connected to said air outlet for causing a circulation of air through said oven chamber, and means for permitting the heating means to operate only when the 65 air-circulating means is in operation.

6. In an electric oven, the combination with an oven chamber having an outlet for air and volatile vapor, means for electrically heating said oven, and means for controlling 70 said electrical heating means, of means for drawing air and volatile vapor through said outlet, and means for permitting the operation of the heating means only when a predetermined amount of air and volatile vapor 75 is being drawn through said outlet.

In testimony whereof I have hereunto subscribed my name this 19th day of May, 1919.

WIRT S. SCOTT.

Correction in Letters Patent No. 1,358,790.

It is hereby certified that in Letters Patent No. 1,358,790, granted November 16, 1920, upon the application of Wirt S. Scott, of Edgewood Park, Pennsylvania, for an improvement in "Control Systems for Ventilating Apparatus," an error appears in the printed specification requiring correction as follows: Page 1, line 53, for the word "exterior" read *interior*; and that the said Letters Patent should be read with this correction therein that the same may conform to the record of the case in the Patent Office.

Signed and sealed this 1st day of February, A. D., 1921.

[SEAL.]

L. B. MANN,

Acting Commissioner of Patents.
